OPAQUE HAIR TREATING COMPOSITIONS

Solomon D. Gershon, Melvin A. Goldberg, and William R. Netzbandt, Chicago, Ill., assignors to Lever Brothers Company, New York, N. Y., a corporation of Maine

No Drawing. Application November 15, 1950,
Serial No. 195,902

3 Claims. (Cl. 167—87.1)

1

This invention relates to an opaque liquid base for hair treating lotions, containing an opacifier which is a finely divided aqueous dispersion of polystyrene and a non-ionic wetting agent, such as an ether, thio-ether, or ester derivative of a polyethylene glycol of an average molecular weight of about 300 to 1500, preferably about 900. The invention also relates to hair molding lotions containing this base together with a keratin reducing agent such as a salt, ester or amide of thioglycolic acid.

Various keratin reducing agents have been suggested for use in cold hair molding, i. e., hair waving or hair straightening preparations, and of these, derivatives of thioglycolic acid have attained a measure of prominence. Analogous substituted organic mercaptans containing a polar group may also be used. Generally, the concentration of the keratin reducing agent in aqueous solution is less than 15% by weight, and generally the pH of the solution is in the range of about 7.0 to about 10.0, a pH of about 9.2 to 9.5 being desirable.

It has been common practice to market these hair molding compositions in an aqueous solution containing some ingredient to impart a creamy appearance. The public, to a large extent, has come to associate such compositions with their appearance. Thus a composition which has a translucent, opalescent or "watery" appearance is not thought to be as desirable as one which has a dense white, creamy appearance and retains its whiteness and opacity under strong light, either reflected or transmitted.

In accordance with the invention it has been found that a finely divided aqueous dispersion of polystyrene and a non-ionic wetting agent, such as a higher alkyl substitution derivative of a moderately high molecular weight polyethylene glycol provides a composition that has the desired opacity and is otherwise an especially advantageous base for hair molding compositions. When this is blended with the keratin reducing agent to form a composition having a suitable pH, an attractive white, creamy appearing, opaque hair molding preparation is obtained. This preparation is very stable against separation of the suspension. While it has a white opaque appearance which is highly desirable yet it may be conveniently applied to the hair so as to con-

2

tact each and every strand of the hair with an ample amount of keratin reducing agent of the desired concentration. This facilitates the obtention of a substantially even chemical effect upon each strand of hair undergoing treatment, so that the same hair forming effect will be obtained throughout each strand of hair, as desired, for all strands of hair being treated. In order to obtain an attractive permanent waving, it is important that the waving effect be imparted equally throughout each strand of hair undergoing treatment, and also equally between the various strands of hair. The compositions of the invention are admirably suited for this purpose, notwithstanding their great opacity. In addition, they can be thoroughly removed from the hair by rinsing, at the end of the treatment.

The objects achieved in accordance with the invention include the provision of a stable, efficient, opaque, white, hair molding composition, and other objects which will be apparent as details or embodiments of the invention are set forth hereinafter.

In order to facilitate a clear understanding of the invention, a preferred specific embodiment is included at the outset.

EXAMPLE 1

Formulation of cream hair molding composition

	Gm.
Thioglycolic acid	61.0
Sodium hydroxide	27.5
Ammonia	5.8
Lauryl ether of polyethylene glycol (m. w. 900)	10.0
Polystyrene	2.06
Water, distilled	891.5

In making up this composition, a finely divided aqueous dispersion of the polystyrene and the lauryl ether is made up. A finely divided amorphous polystyrene may be prepared in accordance with known methods, or obtained from commercial suppliers. A commercial material may contain small amounts of wetting or dispersing agents. These agents may be removed by washing the dispersion with water. However, it has been found that such washing is not necessary, and that the commercially available materials may be blended in accordance with the invention

to provide the cream base. This base may be made up by mixing:

	Gm.
Amorphous polystyrene latex (40 wt. per cent)	5.15
Lauryl ether of polyethylene glycol	10.00
Distilled water	16.18
Aromatic perfume (optional)	2.00

These materials are thoroughly mixed, e. g., by high speed agitation, to provide the opaque base, which is added to a concentrate formed of:

20	Aqueous thioglycolic acid (71.5 wt. per cent)	gm.	85.5
21	Aqueous sodium hydroxide (7.5 N)	ml.	92.0
22	Aqueous ammonium hydroxide (28 wt. per cent)	ml.	23.0

Distilled water to make total of 950 ml.

These materials are thoroughly mixed, e. g., by high speed agitation, with distilled water to make a total of 1000 ml., to give a stable opaque, white cold hair waving or straightening composition.

The polystyrene latex may be made by polymerization of an aqueous dispersion of monomeric styrene, as known in the art. An alternative procedure is to form a solution of the polymer in a suitable solvent, make an aqueous dispersion thereof, and then remove the solvent, e. g., by extraction, drying, or the like.

In a preferred commercially available polystyrene latex, the polystyrene particles are substantially spherical, nicknamed "billiard balls," and consist of particles of extremely small diameter, about 70 to 90% of which are of uniform diameter, and the remainder are somewhat similar. The polystyrene is non-sticky and does not undergo chemical decomposition or changes in the presence of the other ingredients of the composition. It is believed that the greater opacity of the compositions of the invention is associated with the spherical shape and fine particle size of the polystyrene in combination with a relatively large amount of the non-ionic wetting agent. This is a marked improvement over opacifiers or thickeners that have been suggested heretofore.

In order to compare the superiority of the liquid base made in accordance with the invention with the conventional bases of the prior art, a composition was prepared in accordance with Example 1. It had a dense white appearance and did not lose its white appearance when viewed by strong transmitted light or when viewed by reflected light against a black background.

For comparison, a composition was made up having the same amount of polymer solids but employing a polyacrylate such as disclosed in the prior patent literature. This composition had a more gray appearance in ordinary light. The gray appearance was very marked when viewed by reflected light against a black background. It had an opalescent, translucent appearance when viewed in strong transmitted light.

The relative opacities of the two compositions were determined using a General Electric spectrophotometer and transparent Lucite cells in reflectance measuring position. The Lucite cells had a front window 0.050 inch thick, path length 0.050 inch and back window $\frac{1}{16}$ inch. The light getting back into the integrating sphere from this system with both standard black and white backgrounds against the back of the cell was recorded.

The data obtained demonstrated major differences between the compositions. The polystyrene composition was very opaque at all wave lengths.

The polyacrylate composition is less than half as opaque at the violet end and almost entirely transparent at the red, making the polystyrene composition considerably superior with respect to opacity under varying conditions of viewing.

The following numerical data, based on black background readings, support these statements:

Composition	Wave Length (millimicrons)	Total Light Reflected, percent
Polystyrene	400	31
Polyacrylate	400	12
Polystyrene	700	16.3
Polyacrylate	700	2.0

If the data is expressed in a manner analogous to that adopted by the Technical Association of the Pulp & Paper Industry for contrast ratios of paper, the following values are obtained:

Composition	Wave Length (millimicrons)	Total Light Reflected, percent	
25	Polystyrene	400	71.5
26	Polyacrylate	400	55.0
27	Polystyrene	700	46.5
28	Polyacrylate	700	17.8

On the whole, it may be said that the polystyrene composition is at least twice as opaque as the polyacrylate composition.

The commercially available polystyrene latices, e. g., contain about 30 to 50 weight per cent of polystyrene. They are well known in the art and disclosed in the technical literature.

The non-ionic lauryl ether serves to emulsify or disperse the polystyrene to give an opaque emulsion, which is stable and does not separate upon incorporation therein of the keratin reducing agent, e. g., thioglycolate. The preferred ether may be represented by the formula

45 i. e., the monolauryl ether of polyethylene glycol of an average molecular weight of about 300 to 1500, preferably 900. The lauric radical can be replaced by similar radicals having 10 to 18 carbon atoms.

50 In the broader aspects of the invention, not necessarily fully equivalent to the above, there may be used in place of the lauryl ether, a mono-lauric acid ester of polyethylene glycol of an average molecular weight of about 300 to 1500, or a mono iso-octylphenyl ether of a polyethylene glycol of about 300 to 1500 average molecular weight, or a tertiary dodecyl mono thioether of a polyethylene glycol of about 300 to 1500 average molecular weight, or equivalent non-ionic material.

55 Where all of the advantages associated with the above non-ionic type dispersing agents are not required, there may be used instead one of the following dispersing agents: a condensation product of a fatty acid chloride with a partially hydrolyzed protein (e. g., a product known commercially as "Maypon 4C"), or a sulfonated alkylated aryl ether of a polyethylene glycol of about 600 average molecular weight.

60 The amount of the lauryl ether or the like non-ionic dispersing agent may be in the range of 100 to 1000% (by weight) preferably about 500% based on the polystyrene content of the latex.

65 The keratin reducing agent may be an amide, ester, salt or other derivative of a substituted

mercaptan, i. e., a mercapto alkanoic acid such as thioglycolic acid, or thioglycerol. These compounds are known in the art and our invention is not concerned with their novelty. They can be used in the amount known in the art to achieve the desired hair molding depending in part also on the alkalinity of the composition and the speed of molding desired. The alkaline agent may be ammonia, an amine or other nitrogenous base, an alkali metal hydroxide, or other alkaline compound or mixture as known in the art and may be used in an amount to achieve the desired alkalinity also as known in the art.

The foregoing descriptions are for purposes of illustration, and variations and modifications may be made therein within the scope of the appended claims.

We claim:

1. A cream hair molding composition for hair treating which comprises a substantial proportion of a keratin reducing agent dissolved in a finely divided aqueous dispersion of a substantially saturated amorphous solid polystyrene and about 100% to 1000% by weight of a non-ionic dispersing agent based on the polystyrene.
2. The composition of claim 1 wherein the non-ionic dispersing agent is a substitution derivative of a polyethylene glycol having an average molecular weight of about 300 to 1500 which derivative has a lipophilic hydrocarbon group of 10 to 18 carbon atoms.
3. The composition of claim 2 wherein the

derivative is the lauryl ether of polyethylene glycol of an average molecular weight of about 900 and is present in an amount of about 500% based on the polystyrene.
